UNITED STATES PATENT OFFICE.

CHESTER T. MINKLER, OF NEWPORT, RHODE ISLAND.

HYDROSTATIC MINE.

1,368,569.

Specification of Letters Patent. Patented Feb. 15, 1921.

Application filed August 28, 1917. Serial No. 188,542.

To all whom it may concern:

Be it known that I, CHESTER T. MINKLER, a citizen of the United States, residing at Newport, in the county of Newport and 5 State of Rhode Island, have invented certain new and useful Improvements in Hydrostatic Mines, of which the following is a specification.

This invention relates to hydrostatic 10 mines for submarine use and in its more intense aspect to firing devices for mines of the depth charge type or that type adapted to automatically explode on reaching a predetermined depth beneath the surface, although with slight modification the firing 15 device is applicable to other types of explosive devices.

One object of the present invention is to 20 provide a reliable and efficient hydrostatic mine of simple and practical construction. A further object is to provide a firing device, capable of use in connection with hydrostatic mines of various types, having relatively few parts which will be inexpensive to manufacture and easy to assemble.

A further object is to provide a firing device of the above character which may be easily and quickly set to explode at any depth within desired limits, or which may be 30 set at "safety" position to positively prevent premature explosion.

Other objects will, in part, be hereinafter pointed out or in part appear obvious from the following description.

The invention accordingly consists in such 35 features of construction, combination of parts and unique relation of the various members all as more clearly hereinafter outlined and pointed out in the appended 40 claims.

In the accompanying drawings wherein is shown one of various possible modifications, and in the several figures of which corresponding reference numerals denote 45 corresponding parts;

Figure 1 is a vertical sectional view, showing a complete hydrostatic mine of the depth charge type.

Fig. 2 is a vertical or longitudinal sectional view of the firing device.

Fig. 3 is a detailed plan view of the depth setting device.

Fig. 4 is a detail view of a portion of the depth setting device taken on the line 4-4 55 Fig. 2.

Fig. 5 is a detail transverse sectional view taken on the line 5-5 Fig. 2. Fig. 6 is an enlarged detail view.

The invention will hereinafter be described with relation to its application to 60 hydrostatic mines of the depth charge type. It is, of course, to be understood that other forms of mines may be equipped with substantially the same firing apparatus, which constitutes the principal feature of the 65 present invention, without material modification.

Referring now to the drawings in detail and more particularly to Fig. 1, 5 denotes the outer casing which may be assumed to be 70 of general cylindrical shape and of any desired size, according to the explosive charge which it is designed to contain. The casing is provided with concave ends, 6 and 7, as shown for protecting a primer extended and 75 releasing mechanism, A, as shown at the bottom of the figure, while the other end houses a firing mechanism including the hydrostatic actuating and setting mechanism B, and the actual firing mechanism C. 80 Intermediate the ends of the casing is a detonator envelop D.

The primer extender and releasing mechanism A forms no part of the present invention except in so far as it may broadly 85 enter into certain combinations hereinafter set forth and for that reason a detailed description is believed to be unnecessary. It is sufficient to state that the mechanism consists broadly of a hydrostatic piston operatively connected with the envelop D and opposed in its action by resilient means of known strength, the action of water pressure on said piston serving to move the envelop into such proximity of the detonator 90 that 95 the firing of the detonator will explode the charge in the envelop. Until the envelop is drawn to within a certain distance of the detonator, the firing of the detonator will not explode the charge in the envelop. A somewhat similar type of mechanism is shown, for example, in the copending application of Simon P. Fullinwider filed November 28, 1917. The casing, of course, is provided with suitable handling means 100 as desired.

The firing mechanism, B-C, which is shown more clearly in Fig. 2, comprises a cylindrical casing 11 secured at one end to a ring 12 firmly seated in the concave end 110

plate 7 of the mine casing. The opposite end is provided with a contracted collar 13 adapted to support one end of a tube 14 containing the detonator envelop D, the opposite end of which tube 14 is rigidly secured to an annular ring 15 fixed in the opposite end wall 6 of the casing.

A casing flange 16 is bolted or otherwise rigidly secured to the annular ring 12 and 10 carries a mechanism casing 17 of general cylindrical shape provided at one end with a contracted threaded boss 18 adapted to engage or receive one end of a tubular casing extension member 20, the opposite end 15 of which member is provided with a threaded end for receiving a detonator holder 21, which in turn carries a detonator 22 held in place by means of a bushing 23. Within the mechanism casing is mounted an expandable diaphragm 24 of any well known type, and of a material such as copper, one end of which is connected with the casing flange ring 16 while the opposite end is connected to a hydro-piston 25, thereby forming 25 an expandible hydrostatic chamber 26 into which water is admitted through a number of small holes 27 about an index dial plate 28 carried by the casing flange 16 and held in place by a follower nut 30.

30 Within the hydrostatic chamber 26 is a depth setting sleeve 31 terminating at one end in a stud projecting outwardly through a central opening in the dial plate 28 for carrying an index pointer 32. This pointer 35 is adapted to coact with a notched index ring 33 as shown more clearly in Fig. 3, and is held in set position by means of a spring 34 located about the projecting stud and within a recess in the index pointer 32.

40 A suitable keep-screw and nut 35 hold the parts in assembled position.

The depth setting sleeve is provided with a pair of oppositely disposed studs 36 screwed into the side walls thereof and 45 adapted to engage in a helical cam slot in the outer face of an adjusting bushing 37, closely fitting the interior of the sleeve, whereby on applying a rotating movement to the sleeve the bushing will be elevated or 50 depressed according to the direction of such rotation. This bushing is centered upon a stud 38 carried by the piston head and provided with a key 40 for slidably engaging the bushing 37. A retaining collar 41 at 55 its free end prevents removal of a variable resistance element such as an auxiliary depth spring 42 coiled about the stem.

The hydro-piston 25 is provided with a boss 39 to which is threaded a cylindrical or 60 tubular extension 43 closely fitting the interior of the casing extension member 20. It will be noted on examining Fig. 2 that the lower part of the casing extension is of slightly smaller diameter to provide a locking shoulder 44 near the center thereof.

This shoulder 44 is adapted to be engaged by locking balls 45 positioned at a plurality of points about the firing unit, in order to hold the same in retracted position until released when the mine reaches the desired 70 depth.

This firing unit includes a shell or cylindrical member 46 closely fitting the smaller diameter of the casing extension 20 and is provided at its end with a firing point 47 adapted to engage the detonator. Within the member 46 is a releasing plunger 48 which closely fits the inner surface of the member 46 and is normally held in telescoped position, as shown in Fig. 2 by means of a spring 50 extending between the firing point 47 and the interior of the releasing plunger 48. It will be noted that while in this position, the locking balls 45 are held in the outward position against the locking shoulder 44 until a relative longitudinal movement between the member 46 and the releasing plunger 48 takes place to permit the balls 45 to be forced by firing spring 49 radially inwardly into the annular cavity 51 formed at the base of the releasing plunger. This releasing plunger 48 is provided with a projecting stem 52 terminating short of the boss projection 39 of the hydro-piston 25.

95 The operation of the firing device is substantially as follows:—

The index pointer 32 is turned to indicate a number on the dial scale 33 shown in Fig. 3 corresponding to the depth at 100 which it is desired to have the mine explode. On turning this index pointer the depth setting sleeve 31 will be rotated and cause the adjusting bushing 37 with the spring 42 carried thereby to move upwardly a pre-determined distance, thereby increasing the resistance to expansion of the hydrostatic chamber and serving as a means to regulate the depth at which the mine will be exploded. The mine is then thrown overboard and the water, entering through the holes 27 in the index dial plate, will cause an expansion of the hydrostatic chamber 26 and a corresponding relative downward movement of the hydro-piston 25 and associated parts as the hydrostatic pressure increases as the mine approaches the predetermined depth. On expansion of the chamber, the stud or boss 39 of the hydro-piston will cause a compression of the firing spring 49 positioned between the boss and firing unit. It will shortly engage the stem 52 of the releasing plunger and move the same longitudinally relative to the outer member against the action of the spring 50 contained therein. After a slight relative movement the locking balls 45 will be forced inwardly from their locking engagement with the shoulder 44 in the casing extension to occupy a position within the annular 115 120 125 130

cavity 51, thereby unlocking the firing device and allowing the firing spring 49 to move the unit bodily and explode the detonator 22. Of course, during this time the 5 detonator envelop D will have been moved upwardly from its safety position as shown in Fig. 1 under the action of the primer extender and releasing mechanism A. The sharp blow of the firing point 47 upon the 10 detonator will explode the entire charge.

It will be noted that the operation of the setting device involves a relative upward movement of the auxiliary depth spring 42 with respect to the collar carried by the hydro-piston stem and the more nearly these 15 are brought together, the greater the depth will be at which the mine is set to explode, for it will be seen that the movement of the hydro-piston is counteracted not only by the firing spring 49 within the casing extension but by the compression of this variable resistance element or auxiliary spring 42.

By completely turning the index pointer 25 32 through substantially two-thirds of a circumference or until it reaches the mark "S" on the dial, shown in Fig. 3, the device will be at safety position. By this operation, the adjusting bushing 37 is moved 30 along the hydro-piston stem 38 until its upper end is substantially in contact with the collar carried by the stem or at least until the distance between these parts is less than the distance between the boss 39 on the hydro-piston and the stem 52 of the releasing 35 plunger. With the device in the safety position, it will be impossible for the hydro-piston and the collar 41 carried thereby to move downwardly an amount sufficient to cause the boss 39 to engage the releasing 40 plunger stem 52 and thereby prematurely or unintentionally explode the mine.

The terms "upwardly" and "downwardly" 45 are purely relative as the mine in use may occupy any position. They are accordingly to be interpreted in connection with the accompanying drawings.

While the present invention is herein described with relation to its application to 50 mines of the depth charge type, it is to be understood that the firing device proper is applicable to hydrostatic mines of the "horn" type, for example. In this case, however, it is unnecessary to apply a setting 55 device. It is sufficient in that case to connect the hydrostatic chamber with the contact horns whereby on the breaking of the horns water will be admitted to the hydrostatic chamber to expand the same and fire 60 the charge as above explained.

From the above, it will be seen the device is of simple and practical construction having relatively few parts, which will be inexpensive to manufacture and assemble. The 65 device is reliable and efficient in use in op-

eration, and safe to handle and operate. In short, the invention is believed to accomplish, among others, all of the objects and advantages herein set forth.

It is believed that the above will so fully 70 reveal the gist of the present invention that others can by applying current knowledge readily adapt the same to various uses and modifications, and the appended claims are intended to cover all of the generic and specific features thereof that may be comprehended within the range of equivalency.

I claim as my invention:—

1. In a firing device, in combination, a casing, a hydrostatic chamber near one end 80 thereof, a detonator, a firing unit normally held in locked position including two relatively movable members, which members are capable of simultaneous common movement, locking mechanism for normally 85 maintaining said unit in locked position, a firing spring interposed between the firing unit and the hydrostatic chamber adapted to be compressed as the chamber expands, and means associated with the chamber and 90 firing unit adapted to cause a relative movement of the parts of the unit to release the locking mechanism and permit a common movement of the movable members whereby the unit is brought into engagement with 95 the detonator by action of the firing spring.

2. In a firing device, in combination, a casing, a hydrostatic chamber near one end thereof, a detonator, a firing unit normally locked in set position including two relatively movable members, which members are capable of a simultaneous common movement, locking means for normally 100 maintaining said unit in locked position, a firing spring interposed between the firing unit and the hydrostatic chamber adapted to be compressed as the chamber expands, means associated with the chamber and firing unit adapted to cause a relative movement of the parts of the unit to release the 105 locking mechanism and permit a common movement of the movable members whereby the unit is moved into engagement with the detonator by action of the firing spring, and means for adjusting the resistance to the 110 expansion of the hydrostatic chamber thereby to regulate the depth at which the firing of the mine will take place.

3. In a firing device, in combination, a casing, a hydrostatic chamber, a detonator, 120 a firing unit and locking mechanism associated therewith including two relatively movable members, which members are capable of a simultaneous common movement, a firing spring interposed between the firing 125 unit and the hydrostatic chamber adapted to be compressed as the chamber expands, means associated with the chamber and firing unit adapted to cause a relative movement of said movable members to release the 130

locking mechanism and permit a common movement of said movable members whereby the unit is moved into engagement with the detonator by action of the firing spring and 5 means for varying the resistance to the expansion of the hydrostatic chamber thereby to regulate the depth at which the firing of the mine will take place, said last mentioned means including a spring within the hydrostatic chamber adapted to be compressed on the expanding of the walls thereof.

4. In a firing device, in combination, a casing, an expansible hydrostatic chamber, a firing unit including two members yieldingly held in normal position and capable of both relative longitudinal and common movement, a firing spring tensioned by the expansion of said hydrostatic chamber, means for holding said unit in locked position to normally maintain said firing spring under tension and means associated with one of said movable members engaged by the hydrostatic chamber after it has expanded a predetermined amount for moving 20 such member relative to the other member thereby to release the locking device and permit a common movement of said members to cause the explosion of the mine.

5. In a firing device, in combination, a casing, an expansible hydrostatic chamber, a firing unit including two members yieldingly held in normal position and capable of both relative longitudinal and common movement, a firing spring tensioned by the expansion of said hydrostatic chamber, means for holding said unit in locking position to normally maintain said firing spring under tension, means associated with one of said movable members engaged by the hydrostatic chamber after it has expanded a predetermined amount for moving such member relative to the other member thereby to release the locking device and permit a common movement of said members to cause the explosion of the mine, and 35 an adjustable resistance element associated with one of the above-mentioned parts whereby the resistance to expansion of said hydrostatic chamber may be regulated.

6. In a firing device, in combination, a casing, an expansible hydrostatic chamber, a firing unit associated therewith, means normally holding the firing unit in locked position and spring firing means interposed 50 between a wall of the expansible hydrostatic chamber and the firing unit, said unit comprising two telescopic members spring held in normal position, one of said members being adapted to be moved by a part of the expansible hydrostatic chamber after the same has expanded a predetermined distance, thereby to release the locking means and permit the explosion of the mine, and 55 an adjustable resistance element associated with one of said members whereby the re-

sistance to expansion of said hydrostatic chamber may be regulated, said adjustable resistance element including a spring within the hydrostatic chamber and means for moving the same relatively to one of the moving 70 parts of said chamber.

7. In a firing device, in combination, a casing, an expansible hydrostatic chamber, a firing unit, locking means normally holding the firing unit in safety position and a 75 spring interposed between the expansible hydrostatic chamber and the firing unit, said unit comprising two relatively movable members spring held in normal position, one of said members being provided with means 80 adapted to be engaged and moved by the expansible hydrostatic chamber after the same has expanded a predetermined distance, thereby to release the locking means and permit the explosion of the mine, a variable resistance-element associated with one of said members whereby the expansion of said hydrostatic chamber may be retarded and a dial and pointer coacting therewith for setting the variable resistance element 85 90 in predetermined position.

8. A hydrostatic mine, comprising in combination a casing carrying an explosive charge, a detonator envelop, detonator, and means for moving the envelop into proximity to the detonator; a firing device therefor comprising a second casing having said detonator at one end and a hydrostatic chamber at its opposite end adapted to expand on submergence of the mine, a firing unit within the casing including a plurality of telescopic parts capable of relative movement, means normally holding said unit in locked position, said chamber including a diaphragm and piston, a spring interposed between the piston and the firing unit adapted to be compressed on expansion of the piston until the piston coacts with one of said telescopic parts of the firing unit to cause relative movement thereof, thereby to release the locking means holding said firing unit and fire the charge.

9. A hydrostatic mine, comprising in combination a casing carrying an explosive charge, a detonator envelop, a detonator, 115 and means for moving the envelop into proximity to the detonator; a firing device therefor comprising a second casing having said detonator at one end, a hydrostatic chamber at its opposite end adapted to expand on submergence of the mine, a firing unit within the casing including a plurality of telescopic parts capable of relative movement, means for normally holding said unit in locked safety position, said chamber including a diaphragm and piston, a spring interposed between the piston and the firing unit adapted to be compressed on expansion of the piston until the piston coacts with one of said telescopic parts of the firing 120 125 130

unit to cause relative movement thereof and thereby to release the locking mechanism and fire the mine, and means associated with said hydrostatic chamber for varying the 5 time at which the charge is to be fired with respect to the depth at which it is submerged.

10. A hydrostatic mine, comprising in combination a casing carrying an explosive charge, a detonator envelop, a detonator and means for moving the envelop into proximity to the detonator; a firing device comprising a second casing including a hydrostatic expansion chamber, a firing unit capable of a 15 bodily movement, a spring interposed between said chamber and said firing unit and adapted to be compressed as the chamber expands, said firing unit including two relatively longitudinally movable members, a 20 locking element normally held in place by one of said members, and means adapted to be engaged by the movable wall of the hydrostatic chamber for causing relative longitudinal movement of the two members 25 to release the locking element and permit the firing unit to be moved bodily under the action of the interposed firing spring to fire the detonator.

11. A hydrostatic mine, comprising in combination a casing carrying an explosive charge, a detonator envelop and a detonator; a firing device therefor comprising a second casing including a hydrostatic expansion chamber, a firing unit capable of a 30 bodily movement, a spring interposed between a movable part of said chamber and said firing unit and adapted to be compressed as the chamber expands, said firing unit including two members closely fitting 35 one within the other and capable of relative movement, a locking element normally held in place by the inner one of said members means adapted to be engaged by the movable wall of the hydrostatic chamber 40 for causing relative movement of the two members to release the locking element and permit the firing unit to be moved bodily under the action of the interposed firing spring, and means for retarding the expansion 45 of said hydrostatic chamber whereby the depth at which the mine will be exploded may be determined.

12. A hydrostatic mine, comprising in combination a casing carrying an explosive 55 charge, a detonator envelop and a detonator, a firing device therefor comprising a second casing including a hydrostatic expansion chamber, a firing unit capable of a bodily movement, a firing spring adapted to 60 be compressed as the chamber expands, said firing unit including two telescopic members capable of relative movement, a locking element normally held in place by one of said telescopic members, means adapted 65 to be engaged by the movable wall of the

hydrostatic chamber for causing relative movement of the two telescopic members to release the locking element and permit the firing unit to be moved bodily under the action of the firing spring, and adjustable 70 means for retarding the expansion of said hydrostatic chamber whereby the depth at which the mine will be exploded may be determined, said means including a movably mounted spring within the hydrostatic 75 chamber adapted to be engaged and compressed by one of the moving parts of said chamber as the chamber expands.

13. A hydrostatic mine, comprising in combination a casing carrying an explosive 80 charge, a detonator envelop, a detonator and means for moving the envelop into proximity to the detonator, a firing device therefor comprising a second casing having said detonator and a firing unit near one end 85 thereof, an expansible hydrostatic chamber near the other end, an intervening mechanism adapted to fire the detonator after the chamber has expanded a predetermined amount, and means for regulating the time 90 of explosion of the mine with respect to its depth beneath the surface, said means including a sleeve within the hydrostatic chamber carrying a block, a spring associated with said block movable toward or 95 from an element carried by one of the movable walls of the chamber, and means for moving this block from without the mine.

14. A hydrostatic mine, comprising in combination a casing carrying an explosive 100 charge, a detonator envelop, a detonator and means for moving the envelop into proximity to the detonator; a firing device therefor comprising a second casing having 105 said detonator and a firing unit near one end thereof, an expansible hydrostatic chamber near the other end, an intervening mechanism adapted to fire the detonator after the chamber has expanded a predetermined amount, and means for regulating 110 the time of explosion of the mine with respect to its depth beneath the surface, said means including a sleeve within the hydrostatic chamber carrying a block, a spring associated with said block movable toward or 115 from an element carried by one of the movable parts of the chamber, and means for moving this block from without the mine, said means including a dial pointer, and a notched dial plate with which said 120 pointer is yieldingly held in set position.

15. A hydrostatic mine, comprising in combination a casing carrying an explosive charge, a detonator envelop, a detonator and means for moving the envelop into proximity to the detonator; a firing device therefor comprising a second casing having said detonator and firing unit near one end thereof, an expansible hydrostatic chamber near 125 the other end, an intervening mechanism 130

adapted to fire the detonator after the chamber has expanded a predetermined amount, and means for regulating the time of explosion of the mine with respect to its depth

- 5 beneath the surface, said means including a sleeve within the hydrostatic chamber carrying a block, a spring associated with the block movable toward or from an element carried by the chamber, and means for moving this block from without the mine, said block and spring when moved to an extreme position providing a safety lock for the firing mechanism.

16. In combination, a firing device for
15 hydrostatic mines comprising an expandible
chamber and detonator, intervening mecha-
nism for firing the detonator after a pre-
determined expansion of the said chamber
takes place, means for regulating the ex-

- 20 takes place, means for regulating the expansion of said chamber comprising a spring positioned therein adapted to be held in relatively fixed position at one end and engaged by a movable part of said expansible chamber at the other end, and means for
25 moving said spring bodily with respect to the expansible wall of said chamber comprising a member having a cam slot, a dial without said chamber, and a pointer coacting with said dial and connected with said
30 member having a cam slot, whereby on rotation of the pointer said member will be moved relatively to the movable wall of said expansible chamber.

17. In combination, a firing device for
35 hydrostatic mines comprising an expansible
chamber, detonator, intervening mechanism
for firing the detonator after a predeter-
mined expansion of the said chamber takes
place, and means for regulating the expan-
40 sion of the said chamber comprising a
spring positioned therein adapted to be held
in relatively fixed position at one end and
engaged by a movable part of said expansi-
ble chamber at the other end, and means for

moving said spring bodily with respect to the expansible wall of said chamber comprising a member having a cam slot, a dial without said chamber, and a pointer coacting with said dial and connected with said member having a cam slot whereby on rotation of the pointer said member will be moved relatively to the movable wall of said expansible chamber, said threaded member and spring when moved to an extreme position being sufficiently close to the movable part of said expansible chamber as to positively prevent the expansion of said chamber to a degree sufficient to explode the detonator.

18. In firing mechanism for submarine mines, the combination of a sleeve, a striker movable endwise therein, balls lying partly in the striker and partly in the sleeve, and a spring pressed locking device in the striker normally preventing movement of the balls.

19. In firing mechanism for submarine mines, the combination of a sleeve, a striker movable endwise therein, balls lying partly in the striker and partly in the sleeve, a spring pressed locking device engaging the 7 balls and holding them in locked position, and a pressure operated stem for releasing said locking device.

20. In firing mechanism for submarine mines, the combination of a sleeve, a striker 7, movable endwise therein, balls lying partly in the striker and partly in the sleeve, a locking device engaging the balls and holding them in locked position, a pressure operated stem for releasing said locking device, and a spring operating on the striker to move it endwise when released and which normally holds said stem out of engagement with the locking device.

Signed at Washington, D. C., this 28th ~~8~~
day of July, 1917.

CHESTER T. MINKLER
